UNITED STATES PATENT OFFICE.

REES REES, OF KAPUNDA, SOUTH AUSTRALIA, AUSTRALIA.

METHOD OF AND MEANS FOR BLOCKING SADDLES FOR STEAM BOILERS.

1,413,492.

Specification of Letters Patent. Patented Apr. 18, 1922.

Application filed September 2, 1921. Serial No. 498,061.

(GRANTED UNDER THE PROVISIONS OF THE ACT OF MARCH 3, 1921, 41 STAT. L. 1813.)

To all whom it may concern:

Be it known that I, REES REES, a subject of the King of Great Britain and Ireland, residing at Smedley Street, Kapunda, State 5 of South Australia, Commonwealth of Australia, have invented a certain new and useful Improved Method of and Means for Blocking Saddles for Steam Boilers, (for which I filed applications as follows: Commonwealth of 10 Australia, 16,198, June 22, 1920; New Zealand, 44,083, July 1, 1920,) Case B, of which the following is a specification.

This invention relates to the blocking from pieces of metal plate of saddles for steam 15 boilers. In particular it relates to the use of three specially constructed dies, one top and two bottom ones, fitted with removable and interchangeable blocks, the bottom die for the second operation being fitted also 20 with two hydraulic rams. The saddle is shaped in two operations, in the first of which it is pressed to more or less resemble a pan with outwardly inclined sides and in the latter the shaping of the saddle is com-

25 pleted by the aid of the two hydraulic rams.

In order that my invention may be clearly understood I will describe the same with reference to the accompanying drawings in which:—

30 Fig. 1 represents a blank of flat plate from which the saddle is to be pressed.

Figs. 2, 3 and 4 represent front, end and perspective views respectively of the finished saddle.

35 Fig. 5 shows a front view and Fig. 6 shows an end view of the top die B with the loose blocks D and E assembled for the first operation.

Fig. 7 is a front view of the bottom die 40 C used in the first operation showing on the right half an outside view, and on the left half a central section with the partially shaped saddle in place.

Fig. 8 is a cross section of the bottom die 45 C and partially blocked saddle A on the line a b of Fig. 7.

Fig. 9 is a front view showing in dotted lines the partially blocked plate A in position between the second bottom die H and the 50 upper die B, the latter being fitted with the removable blocks E and F, and ready for the finishing operation. The bolts which hold the hydraulic ram cases K in place are

omitted in order to show other parts more clearly.

Fig. 10 shows an end elevation of the die H and the hydraulic ram case K. Holes J are shown through which are passed bolts (not shown in the drawings) which hold the two ram cases together and to the block H.

Fig. 11 is central section showing the fully pressed saddle with the two rams fully extended, the top die B lifted out, and the removable blocks F and E ready to be lifted out.

The top die as used in the first operation consists as shown in Figs. 5 and 6 of a main part or body B and removable blocks D and E, the blocks E being held to the body B by countersunk bolts W and the blocks D 70 being held between them. The bottom die as used in the first operation consists as shown in Figs. 7 and 8 of the main part or body C and removable blocks L and M. This bottom die C is much wider at the top than 75 the second bottom die H and well rounded at the top to allow the metal to gather.

A blank A of the shape shown in Fig. 1 is cut from flat steel plate. It is heated in a suitable furnace and then placed on top of 80 the bottom die C. The top die B with the removable blocks D and E as shown in Figs. 5 and 6 is then brought down and the plate is pressed into the bottom die, the plate being shaped as shown by the heavy black section 85 line on the left hand half of the figure and in dotted lines on the right hand half of the figure, also in heavy black section line in Fig. 8.

The second operation is to complete the 90 blocking of the sides and to bring the ends of the plate to fit the steam drums.

This is performed in the die H with the aid of the two hydraulic rams S, one at each end of the block and which are fastened to 95 the block by means of two stout bolts passing through the holes J in the ram cases K, one bolt at the front and one at the back of the die. These bolts are not shown in the drawings.

100 The partly blocked plate A as it is taken from the die C is again placed in the furnace and when of the required heat it is placed in the die H as shown in Figs. 9 and 11. The loose blocks E and F are secured in place 105 on the top die B, the blocks F being substi-

tuted for the blocks D shown in Fig. 1, and the top die B is brought down and holds the blocks E and F and the partly pressed saddle in place as shown in Fig. 9.

5 The hydraulic rams S fitted with their specially shaped heads T are then operated horizontally and press in the ends completing the shaping of the saddle A as shown by the heavy black section line and the dotted lines 10 Fig. 11.

The rams S are then withdrawn, the nuts removed from the bolts attaching the blocks E to the body B, the die B lifted, and the removable blocks E and F then lifted out, 15 and the finished saddle lifted from the block H.

What I claim is:—

1. The method herein described for forming saddles for steam boilers, consisting in 20 subjecting a plate to pressure between dies to give to the plate a pan-like shape; then placing the pan-shaped plate into a bottom die, introducing a top die into the same, and then applying pressure externally to the 25 upper part of the sides of the pan-shaped plate to impart a curve formation thereto and complete the saddle.

2. In means for blocking saddles for steam boilers, a box-like bottom die, a removable 30 block on the bottom of the die, said block

having an irregular upper face and being of less width and length than the bottom of said die, and a vertical removable block at each end of the die, and top die having removable bottom and end blocks.

3. In means for blocking saddles for steam boilers, a box-like bottom die; a removable block on the bottom of the die, said block having an irregular upper face and being of less length and width than the bottom 40 of the die, and a vertical removable block for each end of the die, said blocks resting on the bottom of the die and extending to the upper face thereof.

4. In means for blocking a saddle of substantially the shape shown for a steam boiler a bottom die comprising a main part or body H, removable blocks M, two hydraulic rams S one at each end of the die, and two bolts one at the front and one at the back for securing the rams to the die, substantially of the shape shown and as described.

In testimony that I claim the foregoing as my invention I have signed my name in the presence of two subscribing witnesses 55 this 25th day of July, 1921.

REES REES.
